UNITED STATES PATENT OFFICE

WILLIAM H. FURNESS, OF NATIONAL PARK, NEW JERSEY, ASSIGNOR TO FURNESS CORPORATION, OF PHILADELPHIA, PENNSYLVANIA, A CORPORATION OF NEW JERSEY

CAKE SPOOL

Application filed July 26, 1929. Serial No. 381,199.

This invention relates to cake spools and is especially useful for cakes of artificial silk thread.

The invention will be described in connection with cakes made of cupro-ammonium artificial silk thread, which cakes are subjected to a washing operation to remove the acid employed in the removal of the copper. 50

One of the primary objects of the invention 10 is to provide a spool which will very effectively and uniformly subject the thread to the washing medium.

More specifically it is an object of the invention to provide means for protecting the 15 thread while on such a spool.

I accomplish the foregoing, together with such other objects and advantages as may hereinafter appear, or are incident to my invention, by means of a construction which I 20 have illustrated in the preferred form in the accompanying drawings, wherein—

Fig. 1 is a side elevation of the complete spool with certain of the members thereof broken out to more clearly show the construction, and 25

Fig. 2 is a fragmentary view partially in section and drawn on an enlarged scale to illustrate certain features of the spool.

Referring now to the drawings, the reference character A designates the spool which, in the main, has a spindle portion B and rims 30

7—7. This part of the spool is made of any suitable metal and the spindle portion is provided with a plurality of annular grooves 8.

Over the spindle is placed a screen 9, preferably composed of a copper screening fabric, and over the copper screen I provide a covering 10 of fabric such as cheesecloth, this covering being preferably continued up the 35 sloping sides of the rims 7.

The cake is laid on the cheesecloth, which keeps the thread out of contact with any metal.

The spool is preferably driven by rollers 40 upon which the spool is placed and by which

it is supported, and the wash water is usually applied in the form of a spray at the top of the cake. The cake is pervious and is preferably wound in the manner described in my copending application Serial No. 239,405, 50 filed December 12, 1927 and since issued as Patent No. 1,770,397 on July 15, 1930. Wash water passes through the cake and through the foraminous cheesecloth and copper screen and enters the channels formed by the annular grooves 8 and the overlying copper screen and cheesecloth, running around the channels and passing out through the screen, cheesecloth and cake toward the bottom. Some of the wash water, of course, runs around on the 55 outer periphery, particularly of the upper half, penetrates through the cake and into the channels and thence back through the screen, cheesecloth and cake, as above described. 60

In addition, the multiplicity of annular grooves keeps the water which enters the channels uniformly distributed across the spindle, so that there is uniform distribution of such water through the cake as it flows out 70 of the channels and through the screen, cheesecloth and cake. The provision of such annular grooves also, in the first instance, tends to secure uniform flow, as it were, through the cake to the channels throughout 75 the length of the spindle.

The spool shown is about twelve inches in diameter and about six inches in length, and in Fig. 2 the screen and the cheesecloth are shown in grossly exaggerated form. 80

I claim:

1. A spool for cakes of thread having a plurality of annular grooves on its spindle portions and a foraminous covering over said spindle portion upon which the thread 85 is adapted to be wound.

2. A spool for cakes of thread having a plurality of annular grooves on its spindle portion and a foraminous covering over said spindle portion upon which the thread is 90

adapted to be wound, said foraminous covering consisting of a layer of copper screening and a layer of relatively pervious cloth.

3. A spool for cakes of thread having a
5 spindle portion and rim portions, said
spindle portion being provided with a multi-
plicity of annular grooves throughout its
length and a foraminous covering over the
10 spindle portion cooperating with said grooves
to provide annular channels.

In testimony whereof I have hereunto
signed my name.

WILLIAM H. FURNESS.
